UNITED STATES PATENT OFFICE.

WILLIAM D. KYLE, OF MILWAUKEE, WISCONSIN, ASSIGNOR TO LINE MATERIAL COMPANY, OF SOUTH MILWAUKEE, WISCONSIN, A CORPORATION OF WISCONSIN.

REINFORCED INSULATOR.

Application filed March 9, 1925. Serial No. 14,195.

The invention relates to insulators, more particularly of the type adapted to be secured to a stationary support.

An object of the invention is to provide an insulator which is reenforced by a metallic strap surrounding an end and opposite sides of an insulator body and having a fastening member passing therethrough, an attaching member being secured in the insulator body at one end against relative rotation and projecting through the strap to clamp the insulator body against a support.

Another object of the invention is to provide an insulator of this type in which a threaded attaching member embedded or inserted therein at one end against relative rotation may be turned by means of a tool inserted into a transverse opening in the insulator body without subjecting the re-enforcing strap to twisting strains.

The invention further consists in the several features hereinafter set forth and more particularly defined in the annexed claims.

In the accompanying drawings; Fig. 1 is a top or bottom plan view of an insulator embodying the invention secured to a support;

Fig. 2 is a longitudinal sectional view thereof taken on the line 2-2 of Fig. 1;

Fig. 3 is a rear end view thereof;

Fig. 4 is a perspective view of the attaching strap; and

Fig. 5 is a fragmentary sectional view of a modified form of insulator.

In these drawings, 10 indicates an insulator body of porcelain, or other suitable insulating material, which is provided with a transverse wire-receiving opening 11 and a second transverse opening 12 spaced forwardly from opening 11 and disposed at right-angles thereto. An attaching screw 13 is provided with a polygonal head 14 inserted in a registering polygonal opening 15 in the rear end of the insulator body and there held rigidly in place by a cement or lead filling 16. If lead is used it is preferably calked around the screw to produce a tight fit.

A U-shaped metal strap 17 has an opening 18 in its transverse portion to receive the attaching screw therethrough and has its legs 19 disposed in channels 20 on opposite sides of the insulator. A channel 21 across the end of the insulator is adapted to receive the transverse portion of the strap

where it rests in spaced relation to the adjacent end surfaces 22 on the insulator body. The legs 19 of the strap are provided with aligned openings 23 near their ends adapted to register with the opening 12 in the insulator body to receive therethrough a cotter pin 24 or other suitable fastening element for retaining the strap in place on the insulator body.

When mounting the insulator the attaching screw 13 is started into a support 25 and screwed therein by a turning tool 26 inserted in the transverse opening 11 until the end surfaces 22 of the insulator body are brought into clamping engagement with the support 25, in which position the transverse portion of the reenforcing strap is spaced from the support, as seen in Figs. 1 and 2, so that it will not affect the rigid mounting of the insulator. When turning the attaching screw into the support, the driving force is communicated directly to the head of the screw by reason of its fit in the opening 15, thus avoiding any twisting or distortion of the reenforcing strap which might cause the latter to leave the channels in the insulator body.

The conductor 27 to be supported by the insulator may then be introduced through the opening 11 where it may be held by a suitable tie-wire engaging the groove 11' extending about the head of the insulator and communicating with the opening 11, or the relation of the wires may be reversed. In many instances, a line wire may approach the insulator in such direction as to impose an axial stress on the insulator, and in such cases, the porcelain or other insulating material is relieved of a heavy load by the reinforcing relation of the metal strap. Since the porcelain itself engages the support at substantial radial distances from the attaching screw, the insulator is also properly able to withstand lateral stresses incident to the attachment of the conductor wire at various angles of approach.

In that form of the invention shown in Fig. 5, the insulator body 10' is provided at its rear end with a polygonal opening 15' in which fits the polygonal head 14 of the attaching screw 13, the cement or lead filling being omitted from the opening and the re-enforcing strap serving to retain the head of the screw in the opening. The head of the attaching screw will remain in driving

engagement with the walls of the recess, so that it may be turned directly by the insulator body and thus avoid twisting or distortion of the reenforcing strap.

5. What I claim as new and desire to secure by Letters Patent is:

1. In an insulator, the combination of an insulator body having a pair of spaced transverse openings extending therethrough at 10 right angles to each other, a threaded attaching member having a part embedded against relative rotation in one end of said insulator body and adapted to be turned thereby, a U-shaped metal strap engaging the rear end 15 and opposite sides of the insulator body and provided with an opening in its transverse portion through which said attaching member passes and openings in its leg portions adapted to register with the forward trans- 20 verse opening in said insulator body, and a fastening element passing through said last-named openings for retaining the strap on the insulator body.

2. In an insulator, the combination of an 25 insulator body having a transverse opening extending therethrough and a channel extending transversely across one end at right angles to said transverse opening, a threaded attaching member having a part embedded 30 against relative rotation in said end of the insulator body and adapted to be turned thereby, a metal strap having a portion disposed in said channel in spaced relation to the end surfaces of the insulator body and 35 having laterally-extending parts adapted to engage opposite sides of said insulator body, and a fastening element securing said strap on the insulator body in front of said trans- 40 verse opening, said insulator body being adapted to be screwed into a support with its end abutting thereagainst and said strap being spaced out of clamping engagement with 45 said support.

3. In an insulator, the combination of an 50 insulator body having a pair of spaced transverse openings extending therethrough at right-angles to each other and having a channel extending around one end and opposite sides in the plane of the forward recess, 55 there being an axially disposed polygonal opening in the end of said insulator body and opening at said channel, a threaded attaching member having a polygonal head registering with said polygonal opening and rigidly embedded therein against relative rotation, a U-shaped metal strap disposed in

said channel to engage the end and opposite sides of the insulator body and provided with an opening in said transverse portion through which said attaching member passes 60 and openings in its leg portions adapted to register with the forward transverse opening in said insulator body, and a fastening element passing through said last-named openings for retaining the strap on the insulator body in spaced relation to the end thereof, whereby the end of the insulator body may abut against a support into which said attaching member is screwed.

4. In an insulator, the combination of an 70 insulator body having a transverse opening extending therethrough and a polygonal opening at one end thereof, a threaded attaching member having a polygonal head fitting in said opening to permit turning of 75 said member by the insulator body, a reinforcing strap engaging said end and opposite sides of said insulator body and having an opening through which said attaching member extends, and a fastening element 80 securing said strap on the insulator body in front of said transverse opening.

5. In an insulator, the combination of an insulator body having a transverse opening extending therethrough, an attaching screw 85 secured in one end of said insulator body against relative rotation to permit turning of said screw by said insulator body, a re-enforcing strap engaging said end and opposite sides of said insulator body and having 90 an opening through which said screw passes, and fastening means disposed in front of said transverse opening securing said strap on the insulator body.

6. In an insulator, the combination of an 95 insulator body having a transverse opening therethrough and a transverse channel extending across one end at right angles to said opening, an attaching screw having a 100 part secured in said end of the insulator body against relative rotation to permit turning of the screw by the insulator body, a U-shaped re-enforcing strap having an apertured transverse portion disposed in 105 said channel and having its legs engageable with opposite sides of the insulator body, and fastening means disposed in front of said transverse opening securing said strap on the insulator body.

In testimony whereof, I affix my signature.

WILLIAM D. KYLE.
